(57) **CLAIM**

The ornamental design for the “inner lining of shoe,” as shown and described.

DESCRIPTION

FIG. 1 is a perspective view of a inner lining of shoe showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a cross-sectional perspective view thereof in a practical operation mode, the shoe shown in broken lines forming no part of the claimed design.
